ATTORNEY.

No. 36,793.

Patented February 16, 1904.

UNITED STATES PATENT OFFICE.

WALTER W. CHASE, OF PROVIDENCE, RHODE ISLAND.

DESIGN FOR A CHARM OR SIMILAR ARTICLE.

SPECIFICATION forming part of Design No. 36,793, dated February 16, 1904.

Application filed January 22, 1904. Serial No. 190,242. Term of patent 3½ years.

To all whom it may concern:

Be it known that I, WALTER W. CHASE, a citizen of the United States, residing at Providence, in the county of Providence and State 5 of Rhode Island, have invented a certain new, original, and ornamental Design for a Charm or Similar Article, of which the following is a specification, reference being had therein to the accompanying drawing.

The drawing represents the obverse and reverse of a charm embodying my new design.

What I claim is—

The ornamental design for a charm or similar article, as herein shown.

WALTER W. CHASE.

Witnesses:

HORATIO E. BELLOWES,
WILLIAM E. BROWN.
